PANTHENOL AEROSOL HAIR SPRAY

Saul Howard Rubin, Nutley, N.J., assignor to Hoffmann-La Roche Inc., Nutley, N.J., a corporation of New Jersey

No Drawing. Filed Dec. 12, 1958, Ser. No. 779,841

13 Claims. (Cl. 167—87.1)

This invention relates to improved cosmetic preparations, packaged in forms convenient for use by the consumer; and to methods of using said preparations. More particularly, it relates to aerosol hair sprays and to the application thereof to the hair. The designation "aerosol hair sprays" is used for convenience herein to describe liquid cosmetic preparations of the type intended to be dispensed upon the hair under pressure in the form of liquid-gas aerosols. The invention relates especially to aerosol hair sprays intended to be used as "hair sets" and "hair conditioners," i.e. those which are sprayed upon the hair especially in order to keep the hair in set position or make it manageable when it is combed or coiffed.

Aerosol hair sprays of this general character are well known in the prior art. The hair-setting action has usually been attributed to the presence of a setting ingredient, believed to function at least partly by formation of a film on the hair shaft upon evaporation of the solvent vehicle. In the past, various materials have been used as setting ingredients, especially such materials as shellacs, ethyl cellulose, carboxymethyl cellulose, gum arabic, polyvinyl alcohol, copolymers of vinyl acetate and vinyl pyrrolidone, and—especially important in commercially successful hair spray compositions of the recent past—polyvinylpyrrolidone (PVP).

A fundamental improvement taught by the present invention is the use of panthenol (pantethenyl alcohol) as a setting and hair conditioning ingredient in aerosol hair spray compositions of the type discussed above; if desired, in admixture with prior art hair conditioning ingredients, such as lanolin derivatives, higher aliphatic acid derivatives, higher aliphatic alcohols, esters, and the like; and preferably (but not obligatorily) in the absence of prior art setting ingredients. That is, it is preferred that panthenol be the sole setting ingredient in the hair spray composition.

Panthenol can be employed either in the racemic or in an optically active form, but dl-panthenol is ordinarily preferred.

It will be understood by those skilled in the art that ingredients of the hair spray composition other than the setting ingredient may be of conventional types. Thus, it will often be advantageous to incorporate such materials as perfumes, antistatic agents, auxiliary hair conditioning agents, plasticizers, antihygroscopic agents, and the like. The perfume ingredient can, of course, be chosen to the formulator's taste. Exemplary of antistatic agents contemplated are such materials as: that known under the proprietary designation "Atlas G-263," available from the Hercules Powder Company, Wilmington, Delaware, this material being essentially N-cetyl-N-ethyl-morpholinium ethosulfate; and that known under the proprietary designation "Zelec" NK, available from E. I. duPont de Nemours & Co. (Inc.), Wilmington, Delaware, this material being essentially an anionic composition of alcohol phosphates described in Du Pont Patent 2,676,122. Exemplary of auxiliary hair condition-

2

ing agents contemplated are, for example, myristyl alcohol, cetyl alcohol, stearyl alcohol, isopropyl myristate, polyglycols (e.g. polyethylene glycols, such as "Carbowax" 4000) and lanolin and various of its derivatives, e.g. lanolin esters and polyoxyethylene lanolins. The latter may be conveniently used in the form of the series of materials known by the proprietary designation "Lanogel," available from Robinson Wagner Co., Inc., New York, New York. The various "Lanogel" preparations constitute an array of polyoxyethylene lanolins of varying ethylene oxide polymer chain length, which form aqueous solutions having viscosities ranging from those of free-flowing liquids to those of thick, viscous pastes, depending upon the concentration of the active material. "Lanogel" 21 is a 50% active aqueous gel, forming turbid dispersions in water, which become clear on dilution with ethanol or isopropanol. "Lanogel" 31 is a 50% active aqueous gel, which forms clear aqueous "solutions" (really dispersions) without the addition of alcohol. 20 Where a film forming or setting ingredient is desired in addition to panthenol, it has been found convenient to employ ethyl cellulose "T-10," available from Hercules Powder Company, Wilmington, Delaware; this material being an ethyl cellulose of 48.5-50% ethoxyl content 25 and having a viscosity of 10 centipoises, when measured at 5% concentration and 25° C.

Conventional liquefied gas propellants, of the type employed in prior art aerosol hair sprays, can be employed. It is preferred to employ fluorinated hydrocarbon propellants, of the kind available under the proprietary designation "Freon" from E. I. duPont de Nemours & Co. (Inc.), Wilmington, Delaware; or under the proprietary designation "Genetron" from Allied Chemical & Dye Corporation, New York, New York; or under the proprietary designation "Isotron" from Pennsalt Chemicals Corporation, Philadelphia, Pennsylvania. Useful propellants are those made by compounding mixtures of various "Freon" individuals, e.g. "Freon" 11 (trichloromonofluoromethane), "Freon" 12 (dichlorodifluoromethane) and "Freon" 114 (symmetrical dichlorotetrafluoroethane). Especially useful are mixtures of "Freon" 11 and "Freon" 12, and of "Freon" 12 and "Freon" 114, in the proportions recommended by the manufacturers for pressure ranges of 12-60 p.s.i.g.

45 As distinguished from the propellant—which is discussed above, and which constitutes one of the two major subdivisions of the compositions according to the present invention—the "concentrate" constitutes the other major subdivision of the novel compositions. The concentrate contains those ingredients which are to be applied to the hair and to remain upon the hair, i.e. panthenol and such optional ingredients (e.g. antistatic agents, perfumes, hair conditioners, etc., previously referred to) as the formulator may wish to employ. The concentrate can be made 50 up by dissolving panthenol and the other ingredients in a solvent of conventional type, preferably ethanol. For reasons of economy, it will be obvious to use a denatured alcohol, for example, that known in industry as "SDA No. 40" alcohol. Anhydrous solvents can be employed 55 to advantage, especially when corrosion of the container is a problem.

Ordinarily, the quantity of panthenol employed in the concentrate is such as to provide in the finished hair spray formula a content of from about 0.25% to about 60 10% panthenol, by weight; preferably from about 0.5% to about 1.5%, especially when panthenol is used as substantially the entire film-forming ingredient; and most preferably, about 1% panthenol is employed.

The ratio of concentrate:propellant in the compositions 65 of the invention can be varied over a wide range. Generally, a weight proportion of concentrate:propellant=about 1:2 is preferred, when employing a quantity of

panthenol in the concentrate which is within the above stated preferred range of from about 0.5% to about 1.5% by weight of the finished composition.

The compositions of the invention are conveniently packaged in aerosol container-dispensers of the type employed for consumer goods moving through retail channels. Dispensers of the "beer can" type have been used to advantage, and are referred to in the illustrative examples below; but it should be understood that the invention is not limited to "beer can" dispensers or even can dispensers, since glass bottles, plastic bottles and other types of container-dispensers can be employed if desired.

Similarly, while it has been convenient to package the compositions of the invention in dispensers by the "cold fill" method of packaging, and reference is made specifically to this method in the illustrative examples below, the invention is not limited to the particular method of packaging employed. For example, the compositions can be put into dispensers by a "pressure-fill" method, if desired.

The use of the compositions of the invention is greatly facilitated by the convenience of the form of aerosol spray package in which these compositions are contained and dispensed. Ordinarily, the user will apply the desired amount of aerosol hair dressing directly from the package to the hair after the hair has been coifed. However, it is not excluded that an individual user may prefer to apply the aerosol hair dressing first, and then coif the hair.

This application is a continuation-in-part of my pending prior application Serial No. 752,175, filed July 31, 1958, now abandoned.

The invention is further disclosed in the following examples, which are illustrative but not limitative thereof; wherein percentages are stated by weight:

EXAMPLE 1

A concentrate was made by mixing the following ingredients, in the manner indicated below:

	G.
"Zelec" NK	19.8
"Lanogel" 21	141.75
dl-Panthenol	141.75
Perfume oil	28.35
Anhydrous alcohol, SDA No 40	4,252.5
Subtotal	4,584.15

The alcohol was warmed to 60° C., and the other ingredients were added. The whole was mixed until a uniform solution was obtained. The solution was cooled to 5° C. and allowed to stand at this temperature overnight. It then was filtered through a porcelain candle filter (XFF porosity).

A propellant was made by mixing the following ingredients:

	G.
"Freon" 11	5,754.51
"Freon" 12	3,836.34
Subtotal	9,590.85

The concentrate and propellant were then loaded into aerosol container-dispensers. The container-dispenser employed comprised: (a) a conventional aerosol can, 6 oz. capacity, side seam lead soldered outside, round dome top with 1" curled opening, concave bottom, half pound electrolytic tin plate throughout, no internal coating; (b) an assembled cup-type valve (e.g. Model NN, Precision Valve Corporation, Yonkers, New York), including a polyethylene, mechanical break-up press button and a polyethylene dip tube; and (c) a protective dome (e.g. Model 5, Precision Valve Corporation, supra). A suitable form of container-dispenser is that shown diagrammatically in Figure 7 at page 800 of "Cosmetics Science

and Technology" (ed. Edward Sagarin), published by Interscience Publishers, Inc., New York, N. Y., 1957.

The filling method employed was of the "cold fill" type. The concentrate was cooled to 0° C., and was filled into the aerosol cans, each can being charged with 45.85 g. of concentrate. The propellant, previously cooled to about minus 10° C., was then added to the cans, each can being charged with 95.90 g. of propellant. The valves were inserted into the filled cans, and were crimped on. After filling, the cans were tested for compliance with I.C.C. regulations, and the protective domes were then placed over the valves.

The aerosol hair spray employed in this example had approximately the following percentage composition:

	Percent
"Zelec" NK	0.14
"Lanogel" 21	1.00
dl-Panthenol	1.00
Perfume oil	0.20
Anhydrous alcohol, SDA No. 40	30.00
"Freon" 11	40.60
"Freon" 12	27.06
Total	100.00

In the same manner indicated in Example 1 above, aerosol hair dressing packages were made up, employing compositions having the kinds and percentages of ingredients indicated in the following examples:

EXAMPLE 2

Concentrate

	Percent
"Atlas G-263" (35% aqueous solution)	0.14
"Lanogel" 21	1.00
d-Panthenol	1.00
Perfume oil	0.30
Anhydrous alcohol, SDA No. 40	29.00

	Percent
Subtotal	31.44

Finished formula

	Percent
Above Concentrate	31.44
"Freon" 114	60.00
"Freon" 12	8.56

	Percent

EXAMPLE 7

Concentrate

	Percent
"Zelec" NK	0.14
"Lanogel" 21	0.50
d-Panthenol	0.50
Perfume oil	0.20
Anhydrous alcohol, SDA No. 40	30.00
Subtotal	31.34

Finished formula

Above concentrate	31.34
"Freon" 11	41.20
"Freon" 12	27.46
Total	100.00

I claim:

1. A liquid composition, for dispensing on the hair under pressure as an aerosol, comprising panthenol in an alcoholic solvent and liquefied fluorinated hydrocarbon gas propellant.
2. An aerosol hair spray composition comprising (1) a concentrate containing an alcoholic solvent and panthenol dissolved therein in an amount from about 0.25% to about 10% by weight of the concentrate, and (2) liquefied fluorinated hydrocarbon gas propellant material selected

from the group consisting of trichloromonofluoromethane, dichlorodifluoromethane and symmetrical dichlorotetrafluoroethane.

3. An aerosol hair spray composition comprising (1) a concentrate containing an alcoholic solvent and panthenol dissolved therein in an amount from about 0.5% to about 1.5% by weight of the concentrate and (2) liquefied fluorinated hydrocarbon gas propellant material selected from the group consisting of trichloromonofluoromethane, dichlorodifluoromethane and symmetrical dichlorotetrafluoroethane, the ratio of concentrate:propellant material in said composition being about 1:2.

4. A composition according to claim 3 wherein the panthenol is dl-panthenol.

5. A composition according to claim 3 wherein the panthenol is d-panthenol.

6. A method of setting hair on the human head which comprises applying to the hair an aerosol which contains as the disperse phase panthenol dissolved in an alcoholic solvent as a film-forming ingredient.

7. A method according to claim 6 wherein the panthenol is in dl-form.

8. A method according to claim 7 wherein the hair is coifed before application of the composition.

9. A package comprising a pressure-tight container in the form of a tin plate aerosol can dispenser having a valve-controlled opening and containing a composition for use in producing an aerosol hair spray, said composition consisting essentially of a concentrate containing panthenol, dissolved in an alcoholic solvent, as a film-forming ingredient and a liquefied fluorinated hydrocarbon propellant gas, said composition being confined in the container under the vapor pressure of the propellant.

10. A package according to claim 9 wherein the panthenol is in dl-form.

11. A liquid composition, for dispensing on the hair under pressure as an aerosol, comprising panthenol in ethanol and liquefied fluorinated hydrocarbon gas propellant.

12. A package comprising a pressure-tight container in the form of a tin plate aerosol can dispenser having a valve-controlled opening and containing a composition for use in producing an aerosol hair spray, said composition consisting essentially of a concentrate containing panthenol dissolved in ethanol as a film-forming ingredient and a liquefied fluorinated hydrocarbon propellant gas, said composition being confined in the container under the vapor pressure of the propellant.

13. An aerosol hair spray composition comprising (1) a concentrate containing ethanol and panthenol dissolved therein in an amount from about 0.5% to about 1.5% by weight of the concentrate and (2) liquefied fluorinated hydrocarbon gas propellant material selected from the group consisting of trichloromonofluoromethane, dichlorodifluoromethane and symmetrical dichlorotetrafluoroethane, the ratio of concentrate:propellant material in said composition being about 1:2.
